*Primary Examiner—Lucy Lieberman
Attorney, Agent, or Firm—Knobbe, Martens, Olson & Bear,
LLP*[57] **CLAIM**

The ornamental design for a bottle, as shown and described.

DESCRIPTION

FIG. 1 is a top plan view of a bottle illustrating my new design;

FIG. 2 is a front elevational view of the bottle of FIG. 1. The lower portion of the bottle shown in phantom is shown for illustration purposes only and forms no part of the claimed design;

FIG. 3 is a left side elevational view of the bottle of FIG. 1. The lower portion of the bottle shown in phantom is shown for illustration purposes only and forms no part of the claimed design;

FIG. 4 is a right side elevational view of the bottle of FIG. 1. The lower portion of the bottle shown in phantom is shown for illustration purposes only and forms no part of the claimed design;

FIG. 5 is a rear elevational view of the bottle of FIG. 1. The lower portion of the bottle shown in phantom is shown for illustration purposes only and forms no part of the claimed design; and,

FIG. 6 is a bottom plan view of the bottle of FIG. 1.
